UNITED STATES PATENT OFFICE.

JOHN O. MORRIS, OF WASHINGTON, DISTRICT OF COLUMBIA, ASSIGNOR TO MORRIS SPECIALTY MANUFACTURING COMPANY.

REGISTER.

No. 895,878.

Specification of Letters Patent. Patented Aug. 11, 1908.

Application filed November 19, 1906. Serial No. 344,123.

To all whom it may concern:

Be it known that I, JOHN O. MORRIS, a citizen of the United States, residing at Washington, District of Columbia, have invented 5 certain new and useful Improvements in Registers, of which the following is a specification.

My invention relates to fare registers.

It is the object of my invention to prevent 10 fraud on the part of conductors of street railway cars or the like, and with this object in view I have provided an attachment of special construction for use with fare register by which the attention of passengers and 15 particularly the person who has just paid his fare will be attracted to the fare register so that the conductor will be deterred from omitting the ringing up of a fare with the intention of appropriating the same to his 20 own use.

My attachment includes means whereby after a certain interval, or more properly speaking, after a certain number of fares have been rung up, a sign ticket or like device will be displayed by the operation of the mechanism in ringing up the last fare, which ticket, sign, or other device will entitle the passenger whose fare has just been rung up to an award of some character, such as a 25 ticket or a number of tickets, or a free pass on the road. The interval between the display of the sign ticket or other device is made variable so that neither the conductor nor the passengers will know exactly when the ticket 30 displaying mechanism will display or eject the said ticket or sign, and in this way the attention of the passengers will be constantly directed to the fare register, and their close observation will act as a deterrent to any 35 40 fraudulent intentions on the part of the conductor.

The invention consists in the features, combination and arrangement of parts hereinafter described and particularly pointed 45 out in the claims.

In the accompanying drawings,--Figure 1 is a perspective view of a fare register having my improvements embodied therein. Fig. 2 is an elevation with the casing removed. Fig. 50 3 is an elevation taken from the opposite side of the machine from that shown in Fig. 2. Fig. 4 is an elevation of certain of the mechanism of the fare register, parts however being omitted. Fig. 5 is a plan view of the

ticket printing and ejecting mechanism, constituting my improvement. Fig. 6 is a view of the interchangeable wheel, whereby the interval between the displaying of the sign or ticket may be varied or changed as the officers of the road may determine. Fig. 7 is a view similar to Fig. 3 but showing a modification. Figs. 8, 9 and 10 are detail views showing a detailed group of elements in different positions.

The general form, construction and arrangement of the main portion of the fare register may be any of those well known. The connection from the cord or rock shaft extending along the car is made with the register at the point, 1, and the movement is communicated to the main part of the register through a lever 2, a link 3, a slide bar 4, and a pawl and ratchet 5-6. Cash fares will be registered through a supplemental slide 7 and tickets through a supplemental slide 8, these slides being operated from an extension 9 of the main slide 1. From the shaft 10 of the main ratchet wheel 6 the movement is communicated to the main parts of the register which is shown generally in Fig. 2, some of the power transmitting wheels being indicated at 11-12 and 13. My attachment comprises generally a pair of printing rolls 14-15, Fig. 5, between which pass a strip or tape 16, from a roll 17, the said strip passing out from the machine through a guide 18 of elongated form adapted to closely confine the strip; the said guide being formed at its discharge end with beveled edges 19, it being the purpose to have a conductor tear off the portion of the strip or tape which has been projected beyond the said guides 18.

Motion is communicated to the wheels 14-15 from a beveled gear 20 on the shaft 21; said beveled gear deriving its motion from the train of motion transmitting wheels of the register and communicating its motion to the pinion 22 on a shaft 23, which shaft has thereon a gear wheel 24. This gear wheel meshes with a gear wheel 25 on a shaft 26 and this in turn meshes with the gear wheel 27 on the shaft 28, which shaft extends upwardly and carries the printing roll 15, and the gear 27 of this roll is geared to the roll 14 through the toothed wheel 29 indicated in dotted lines in Fig. 5. I provide also an alarm consisting of a bell 30 suitably

supported by a bracket 31, the hammer 32 of said bell being arranged to be operated by the pins or projections 33 of a disk 34 arranged on the shaft of the gear wheel 25, so that each time the tape or ticket strip is fed to eject or feed a portion of the said strip outside the casing the alarm will be sounded and the attention of the passengers will therefore be more fully directed to the fare register. 10 The printing rolls are supplied with ink through rollers 35. I utilize the printing rolls in the present embodiment of my invention also as the feed rolls.

I provide means whereby the register will 15 be locked each time that one of the tickets, signs or other devices are displayed by projecting the same from the casing of the machine, and for this purpose I associate with the train of mechanism leading to the ejecting means above described, a toothed wheel 36, which in the present instance I arrange on the shaft 21. This wheel has a series of teeth or cam surfaces 37, its general form being that of a ratchet wheel and it is designed 20 to operate a lever 37^x pivoted at 38 and under the tension of a spring 39, tending constantly to force the arm 40 or 'said lever against the ratchet wheel.

Normally, the end of the arm 40 of the 30 lever rests in its lowermost position in the tooth of the ratchet or cam wheel, as indicated in Fig. 9. This lever 37^x controls the action of a locking lever 41 which is pivoted at 42 to the frame and is under tension of a 35 spring 43. The lower end of this lever is connected with a supplemental lever 44 pivoted at 45 to the frame and pivotally connected at its lower end at 46 to a slide 47, which is slotted at 48 and guided on pins 49 40 fixed to the frame. This slide carries a finger 50 adapted to engage a projection 51 of a locking detent 52 pivoted to the frame at 53 and having its tooth 54 adapted to engage a ratchet wheel 55 on the main shaft 10 45 of the main portion of the register. The tendency of the spring 43 acting on the lever 41 is constantly to force the slide 47 towards the left and cause the detent 52 to engage and lock the ratchet wheel 55, and consequently the main portion of the register 50 against action, but this tendency is resisted ordinarily by the lever 37^x above described which presents its end in position to be engaged at 56, Fig. 9, by the end of the lever 55 41. The parts remain in this position at which time the locking detent 52 is out of 60 action until the sign, ticket, rebate or other device is displayed or ejected from the machine, at which time the pinion 20 is moved, as above described, and the cam wheel 37 moving with it in the direction of the arrow, Fig. 3, causes by the action of its cam shaped tooth on the arm 40, the lifting of the lever 37 to the position shown in Figs. 3 and 8 so 65 that the end of the lever 41 is no longer de-

tained, but the said lever under the action of its spring 43 will be operated to the position shown in Fig. 8 and this through the lever 44 and slide 47 will throw the locking detent into action and thus lock the machine. The 70 conductor under these conditions will now have to go to the fare register in order to unlock the machine and he will at the same time tear off or take out from the machine the ticket, rebate, or other device which has 75 been rendered accessible by the ringing up of the last fare and he will present this to the passenger whose fare has just been rung up.

In order to unlock the mechanism so that the next fare may be rung up the conductor 80 pulls upon the knob or button 57, which through its rod 57^x will retract the lever 41 at its upper end and withdraw the locking detent 52 from engagement with the ratchet 55, and at the same time the lever 37 will 85 drop into the position as shown in Fig. 9 so as to hold the lever 41 in its retracted position ready for the next operation.

The device which is displayed or rendered accessible at irregular intervals by the ringing up of the fares may be a ticket, an order 90 on the company for said ticket or tickets, or it may be simply a sign or statement to the effect that the passenger whose last fare has been rung up is entitled to a free ride, or the 95 award may be made in any suitable manner.

In connection with the apparatus above described, I may employ an advertising device, consisting as shown in Fig. 2, of a drum or disk 58 suitably connected with a part of 100 the gearing and designed to be rotated at the time the sign or ticket is displayed or ejected so as to display a suitable advertisement. This drum may consist simply of an extension of the alarm disk or drum 34 and any 105 suitable number of advertisements may be placed thereon. Instead of this form of advertisement I may employ an elongated drum or cylinder as shown at 59 in Fig. 7, this being connected by gears 60, 61 to the 110 train of mechanism above described.

I do not wish to limit myself to the details of construction, arrangement or operation of the parts, as these may be varied without departing from the spirit of my invention. 115

I may vary the interval between the operations of the ticket or sign display mechanism by having an interchangeable wheel, such for instance as that shown in Fig. 6. This wheel is provided with teeth adapted to mesh with 120 teeth 20^x on a wheel connected with the bevelled gear 20. The interchangeable wheel is adapted to be fixed in place by means of two pins which will engage the openings 6^x in the said wheel, these pins being arranged on another wheel or disk 13 shown in Fig. 3. The interchangeable wheel may be held in position by an arm 13^x pivoted to the frame at 13^x and adapted to be swung down in order 125 to place or remove the interchangeable disk 130

or wheel. When in its uppermost position the arm 13^a may be held by a pin or set screw 13^b.

One important result flowing from the use of my invention is that the conductor will be induced to register the fares separately and as soon as they are collected, instead of, as is frequently done now, collecting a large number of fares before ringing any of them up. Of course the conductor does not know at what moment the award delivering device will be operated, and the register locked in position, and in order that he may deliver to the proper party the award it will be necessary for him to register each fare separately instead of collecting a large number before registering. Furthermore, the locking of the register when the award is ejected or displayed requires that a specific or definite operation or manipulation of the apparatus be performed by the conductor before he can proceed with the registration of fares and the liability of the locking taking place at any moment will force the conductor to ring up the fares separately and to deliver to the proper passenger the award before proceeding with the further registration of fares.

I claim as my invention.

1. In combination with a fare register, means for displaying an award to a passenger and locking means for the register independent of the displaying means operating to positively lock the same when the display means has been operated, substantially as described.

2. In combination with a fare register, means for displaying an award to a passenger, and locking means arranged to positively lock the register when said device is displayed, and means whereby the conductor may release the lock, substantially as described.

3. In combination with a fare register, means for displaying an award to a passenger, connections between the register mechanism and the said means for operating the latter at intervals and a lock for the register mechanism, said lock being operated from the connections leading to the display means, and positively obstructing the movement of said register mechanism substantially as described.

4. In combination with a fare register, means for displaying an award, means for locking the register when an award is displayed, connections for operating the same including a member whereby the interval between the operation of said awarding means and locking means may be varied, said mem-

ber being individually interchangeable with- 60
out dismantling the apparatus, substantially as described.

5. In combination with a fare register, means for displaying an award, connections for operating the same from the fare register, 65 locking means and means for operating the same when the award is made consisting of a cam or toothed wheel, the lever operated thereby and connections controlled by the said lever for setting the locking means, sub- 70
stantially as described.

6. In combination with the register, means for displaying an award, connections for operating the same from the register mechanism, a locking pawl for positively locking the 75 register against movement and means for operating the same consisting of the toothed wheel, the lever operated thereby, a second lever to be locked out of position by the first lever, said second lever when released operating the locking pawl, substantially as de- 80
scribed.

7. In combination with fare register mechanism, means for ejecting a ticket, and a connection between the register mechanism and 85 the ejecting means to operate the latter at intervals in respect to the operations of the register mechanism, said connection including an interchangeable member to vary the intervals between the operations of the eject- 90
ing means, substantially as described.

8. In combination with a register, printing rolls arranged to eject an award and print the same, connections for operating said printing rolls at intervals, register mechanism from 95
which the said connections lead to the printing rolls, and locking means for the register operating to positively lock the same when the rollers have been operated to eject an award, substantially as described. 100

9. In combination with registering mechanism, means for displaying an award, connections for operating the award displaying means and locking means with a tooth wheel 105 and detent for controlling the same, substan-
tially as described.

10. In combination with fare registering mechanism, award displaying mechanism, locking means operating when the award is displayed and a toothed wheel controlling 110
said locking means.

In testimony whereof, I affix my signature in presence of two witnesses.

JOHN O. MORRIS.
